DESCRIPTION

U.S. PATENT DOCUMENTS

FIG. 1 is a perspective view of a selector for audio visual apparatus showing our new design;

D. 284,280 * 6/1986 Mack, Jr. et al. D14/124
D. 297,007 * 8/1988 Pushelberg D14/124
D. 370,481 * 6/1996 Brooks D14/124
D. 381,647 * 7/1997 Terng D14/124
D. 399,840 * 10/1998 Curburn et al. D14/124

FIG. 2 is a top plan view thereof;
FIG. 3 is a left side elevational view thereof;
FIG. 4 is a front elevational view thereof;
FIG. 5 is a bottom plan view thereof;
FIG. 6 is a right side elevational view thereof; and,
FIG. 7 is a rear elevational view thereof.
